SHOCKPROOF LOCKING ELECTRICAL PLUG
AND RECEPTACLE

Walter H. Wilson, Mansfield, Ohio

Application February 26, 1953, Serial No. 339,020

8 Claims. (Cl. 200—50)

1

This invention relates to a shock-proof locking electrical plug and receptacle, and has for an object to provide an improved electrical plug and receptacle so cooperating with each other that the plug is first locked in the receptacle as it moves into circuit completing position, and cannot be unlocked from the receptacle until after it has been moved away from the circuit completing position.

A further object of this invention is to provide an electrical plug and receptacle wherein it is very difficult to insert a foreign object in such a manner as to complete a circuit through the receptacle, but wherein if the foreign object happens to be shaped sufficiently close to the shape of the plug, it cannot act to shock the person using the foreign object, but instead, will ground the circuit through the receptacle and probably blow out the fuse.

A further object of this invention is to provide an electrical plug and receptacle wherein when the plug is in circuit completing position, it is locked therein and cannot accidentally or intentionally be removed therefrom until after the circuit has first been broken.

Still a further object of this invention is to provide an electrical receptacle which will either resist the entrance of a foreign object therein, or will short circuit and ground, should the foreign object be successfully manipulated to reach and complete the circuit thereto.

Still a further object of this invention is to provide a shock-proof receptacle for a male electrical plug wherein a foreign object will have difficulty in completing a circuit, but if it does succeed in completing the circuit, then the circuit will be completed only by grounding it through the receptacle, and thus, blowing any fuse on the line, and in any case, preventing any shock from reaching the person using the foreign object in the receptacle. In this way, a small child inserting a foreign object in the receptacle, such as a nail, hair pin, or darning needle, or the like, could probably not succeed in operating the receptacle to complete the circuit, or if a child did succeed in completing the circuit, the circuit when completed would ground through the receptacle, and would not shock the child.

Still a further object of this invention is to provide a shock-proof locking electrical plug and receptacle wherein the receptacle is usually so placed in a wall that the plug must be inserted in a horizontal direction, and then, after completely inserted must be moved downwardly somewhat, first causing the plug to be locked

in the receptacle, and then, after it is so locked, completing the circuit from the receptacle to the plug, making it impossible to remove the plug while the circuit is complete, but necessitating that the plug be first lifted to interrupt the circuit, and then, lift it further to the horizontal position to unlock the plug before it can be removed. Thus, the weight of the plug with the assistance of the toggle spring tends to hold the receptacle in the locked circuit completing position and prevents its accidental removal therefrom without first deliberately lifting the plug up to the horizontal position.

Still a further object of this invention is to provide a plug receiving receptacle which has a rotatable disc having the plug socket therein, which extends slightly beyond the surface of the remainder of the receptacle, and thus, of a wall in which it may be mounted, thus, it making it easy to find the receptacle and insert it by feel even in the dark.

Still a further object of this invention is to provide a shock-proof locking receptacle whose external parts can lend themselves to any durable decorative material without diminishing the serviceability thereof.

With the foregoing and other objects in view, this invention comprises the combination, construction and arrangement of parts hereinafter set forth, claimed and disclosed in the accompanying drawings, wherein:

Fig. 1 is a side elevational view of the receptacle as mounted on a wall joist, with the receptacle still in closed position, although the plug has been partially inserted.

Fig. 2 is a top edge elevational view of Fig. 1.

Fig. 3 is a bottom edge elevational view of Fig. 1.

Fig. 4 is a sectional view on line 4—4 of Fig. 1.

Fig. 5 is a sectional view similar to Fig. 4,

but with the plug fully depressed, but not yet rotated.

Fig. 6 is a side elevational view, omitting the near side frame plate of the receptacle, with the plug rotated to locked and to circuit completing position.

Fig. 7 is an exploded perspective view of the receptacle and of the plug.

Fig. 8 is a perspective view of the receptacle and plug mounted in a wall in operative position.

There is shown at 10 the shock-proof receptacle arranged to receive and lock therewithin the one prong electrical plug 11 when the plug is in circuit completing position.

The electrical plug 11 of this invention comprises an axially extending contact rod 12 in-

sulatably supported concentrically within a contact sleeve 14, contact sleeve 14 having an enlarged portion 15 through which electrical conductors 16 extend, the enlarged portion 15 being cut away so that one of the conductors 16 may be secured as at 17 to the axially extending rod 12, and the other conductor 16 is secured as at 18 to the enlarged portion 15 of the sleeve 14.

As a result of the cutaways 20 in the enlarged contact sleeve portion 15, the securing screws 17 and 18 are countersunk below the surface of the enlarged portion of the sleeve 15, and an insulating jacket 21, of ceramic or other suitable insulating material, is slid over the enlarged sleeve portion 15 and secured thereto, as by a screw 22. The insulating jacket 21, thus, provides a handle for manipulating the plug 11. The external end of the contact sleeve proper 14 is provided with a circumferential groove 23, and beyond the groove 23, there is provided a conically shaped end 24 on the contact sleeve 14, the sleeve 14 having the axial contact rod 12 provided with a contact end 25 extending therebeyond and insulated from the sleeve 14 by the same insulating material that extends concentrically between the rod 12 and the sleeve 14, and maintains in insulated concentric relation.

The receptacle 10 comprises a pair of side frame members 30 and 31 of metal or other conductive material secured together by means of stud bolts 32 passing through appropriate apertures 33 in plate 30 and threaded into suitably threaded apertures 34 in the other plate 31, although obviously nuts could be provided instead of the threads in the apertures 34. The plates 30 and 31 are held in proper spaced parallel relationship to each other by means of sleeves 35 and a sleeve portion 36, which act to space the plates in proper relationship to each other. Both plates 30 and 31 are provided with out-turned flanges 37 and 38, having suitable apertures 40 through which wood screws 41 may be inserted for mounting the receptacle 10 on a suitable support, such as, a joist, or the like 42, within a wall 56.

Journalled between conductor plates 30 and 31 is a socket disc 43 having a socket opening 44 of uniform diameter to receive the sleeve proper 14 therethrough, the diameter of the disc 43 being substantially equal to the length of the sleeve proper 14 between the shoulder joining it to the sleeve enlargement 15 at one end, and a circumferential groove 23 at the other end, so that when the plug 11 is inserted within the socket opening 44 of the disc 43, the circumferential groove 23 will extend just beyond the inner end of socket opening 44. Radially aligned with the socket opening 44 at the inner end thereof is a transverse slot 45. The disc 43 has axle ends 46 extending therefrom and journalled in bearing openings 47 in the plates 30 and 31.

The disc 43 has a link 49 integrally secured thereto at one end, and its other end is pivoted by a screw 50 between a bifurcated end 50 of a spring plunger 51 about which there extends a compression coil spring 52 biased within a U-shaped well 53 which is journalled by means of pins 54 in apertures 55 in the side plates 30 and 31, providing a toggle member which yieldably resists the initial rotation of the disc, and then assists its final rotation. As one limit of rotation, the socket opening 44 extends in a horizontal position with the plug 11 in horizontal

position when the device is mounted in a wall, as shown at 56 in Fig. 8. In this position, as also shown in Fig. 1, a portion of the toggle member abuts against an inturned tongue 57 at one end of side frame plate 31, this inturned tongue 57 having an extending tab 58 apertured as at 60 and threaded to receive a stud screw 61 and hold a wall plate 62 in position thereon, a similar tab 57 and tongue 58 being provided at the other outer end of plate 31.

Cooperating with the radial slot 45 of the disc 43 is the latch member 63 having bifurcated prongs 64 which are guided in guide slots 69 in the side frame plate members 30 and 31, and a latch member 63 being provided with a compression spring 65 extending about the latch member plunger 66, and biased between the prongs 64 and an apertured sleeve 67 secured by pins 68 extending through apertures 70 in the side frame plates 30 and 31. In order to permit the plunger 66 to retract and compress the spring 65, a well 71 is provided in the supporting joist 42, although obviously the side frame plates 30 and 31 could be made sufficiently longer so as to avoid the necessity for the well 71. Also, the well 71 could be omitted by either shortening the end of plunger 66, or reducing the depth of the disc slot 45, or both, thus shortening the length of the plunger travel so as not to exceed the length of the receptacle proper.

Extending inwardly from the prongs or bifurcated fingers 64 are projecting edges bevelled as at 72 and complementary to the conical end 24 of the contact sleeve 14, so that when the sleeve 14 is inserted through the socket opening 44 in disc 43, the conical end 24 will abut against the bevelled edges 72 to expel the fingers or prongs 64 from the radial slot 45 against the resistance of the spring 65. To prevent the prongs or fingers 64 from being spread apart by the action of the conical end 24 of sleeve 14, guide reinforcing plates 73 are secured on the outer surfaces of the side frame plates 30 and 31 over the outer ends of the guide slot 69, and of a size so that the outer edges of fingers or prongs 64 will still be in contact therewith when the latch member 63 has moved inwardly the maximum distance against the spring 65. The slots 69 and plates 73 thus act to guide the fingers or prongs 64 in their travel.

Between the lower portions of the fingers or prongs 64 and beyond the bevelled edges 72, as viewed from the outside of the receptacle, there is provided a bevelled deflector plate 74 having a deflector of bevelled surface in axial alignment with the socket opening 44 when the fingers or prongs 64 are engaged and latched in the regular slot 45. If a small object such as a hair pin is inserted through the socket opening 44 and slips between the bevelled edges 72, it will be deflected by this deflector plate 74, rather than press thereagainst, and thus, serve to minimize the possibility that a foreign object would operate the same.

Extending from the sleeve portion 36 are a pair of prongs 75 spaced apart the proper distance so that they may fit into a circumferential groove 23 of a contact sleeve 14 and prevent the contact sleeve 14, and thus, the plug 11 from being withdrawn so long as they are in cooperative position. These prongs 75 are contoured to the periphery of the disc 43 and lie closely thereagainst, a tab 76 extending on the other side of the sleeve portion 36, tending to contact the periphery of disc 43, and thus, pre-

venting any pivoted movement of the plug locking prongs 75.

As will be apparent, insertion of the plug 11 into the receptacle 10 will cause the sleeve 14 to slide through the socket opening 44, its conical end 24 abutting the bevelled edges 72 of fingers or prongs 64, will expel the latch member 63 from the radial slot 45 permitting the disc 43 to be rotated by means of the plug from the position shown in dotted line in Fig. 8 to the position shown in full line in Fig. 8. As this happens, the conical end 24 will move out from between the bevelled edges 72, and the latch member 63 will be held in retracted position by means of the ends 77 of prongs 64 abutting against the periphery of disc 43. The circumferential groove 23 will then enter between the plug locking prongs 75 as the toggle member spring 52 is first compressed and then expands beyond its dead center to urge the disc to complete its rotation. The contact end 25 of the center contact rod 12 extends between and beyond the locking prongs 75, and comes into mechanical and electrical contact with a positive contact terminal 80 having a terminal tongue 81 suitably supported in the path of the contact rod contact end 25, thus providing a limit for the rotation of the disc 43 in this direction.

This contact terminal 80 is supported on the outside of a pair of insulating plates 82 and 83, which are supported and secured by means of bolts or screws 84 to apertures in the tab 57, already described on the plate 31, and a similar tab 85 at the other end of the same plate 31. The plate 83 is placed inside of the two tabs 57 and 85 between the plates 30 and 31, and the other insulating plate 82 is secured on the outside of these same two tabs 57 and 85. Both insulating plates 82 and 83, made of any suitable rigid insulating material, are provided with longitudinal slots 86 and 87. The contact terminal 80 is secured on the outer plate 82 by bolts and nuts 88 and 90, with its contact tongue 81 bent inwardly so as to point approximately toward the center of the disc 43, while the contact end 25 of the contact rod 12, when inserted through the socket opening 44 and rotated, will just extend through the slot 86 in the inner insulating plate 83 and come into abutting mechanical and electrical contact with the contact tongue 81, as clearly illustrated in Fig. 6. An electrical conductor 91 is suitably secured between the nuts 90 for providing the positive side of the circuit, and a second or negative electrical conductor 92 is secured by a nut and bolt 93 to the conductive side frame plate 31 as by being secured on its flange 38.

In operation, the receptacle 10 will be mounted in a wall 56, as shown in Fig. 8, with a portion of the disc 43 beyond the wall plate 62 extending beyond the surface of the wall 56, thus, making it easy to locate the socket opening therein. The plug 11 will be inserted into the socket opening in the disc 43 in a horizontal direction, and then, rotated downwardly to the limit of its rotation, as shown in dotted lines in Fig. 8, thus, both locking the plug 11 in the socket opening and completing the circuit from the positive electric conductor 91 to the plug conductors 16, and back to the negative conductor 93.

As the plug 11 is inserted, the conical end 24 of the contact sleeve 14 abuts the bevelled inner edges 72 of the fingers or prongs 64 expelling the latch member 63 therefrom, and permitting the disc 43 to commence its rotation, the circumferential groove then entering between and locking

70
75

within the locking prongs 75, and finally the contact end 25 abutting against the contact tongue 81 to complete the circuit.

Inasmuch as the contact sleeve 14 is in contact with the socket opening 44 of disc 43, it makes an electrical connection through the disc 43 and the conductive side plate to the negative conductor 92. Thus, contact is made with the negative side of the circuit as soon as the sleeve enters the socket opening, and is not completed to the positive side of the circuit until after the disc has been unlatched, partly rotated to lock the plug in position, and then, completely rotated to make the positive contact. Before the plug 11 can be withdrawn intentionally or accidentally, it must first be moved to rotate the disc 43 in the opposite direction, thus, first breaking the positive side of the circuit by moving the contact end 25 away from the contact tongue 81, then releasing the circumferential groove 23 of contact sleeve 14 from between the locking prongs 75, and then, finally withdrawing the same in the horizontal position of Fig. 8, and the latch 63 is simultaneously moved into latching position by its spring 65 as its fingers or prongs 64 re-enter the radial slot 45 to hold the disc 43 against accidental rotation.

Should a foreign object be inserted through the socket opening 44, as by a child, for instance, its entry will be resisted by the bevelled edges 72 of the fingers 64. If the object is too large to pass between these fingers, then, of course, it can never reach in far enough to reach the positive contact tongue, even though it may be strong enough to press and expel the latch member 63. If small enough to fit between the bevelled edges, it may also be weak enough to be deflected by the deflector plate 74, and thus, prevent any accidental operation. Should the foreign object be of conductive material and happen to be of proper size and shape to actually unlatch the latching fingers 64 and rotate the disc, and fit between the locking prongs 75, such as when the foreign object may be a strong, thin darning needle, then if the foreign object should finally reach the internal contact 80 or its contact finger 81, then the most that would happen would be that the circuit from the positive conductor 91 going through the end of the foreign object would be grounded through the disc 43 to the side plate 31 and the negative conductor 92, probably blowing the fuse, but in any case, avoiding any shock to the child inserting the foreign object.

Applicant's receptacle is thus shock-proof against the insertion of any foreign object, and in addition, serves to lock the plug 11 in circuit completing position against accidental removal while the circuit is complete, necessitating the breaking of the circuit prior to the removal of the plug from the receptacle.

While the device has been shown and the structure described in detail, it is obvious that this invention is not to be considered as being limited to the exact form disclosed, and that changes in detail and construction may be made therein within the scope of what is claimed, without departing from the spirit of this invention.

Having thus set forth and disclosed the nature of this invention, what is claimed is:

1. In combination, a shock-proof locking electrical plug and receptacle comprising an axially extending contact rod, a contact sleeve insulately supported on said contact rod having one end thereof spaced from an extending contact end of said contact rod, said contact sleeve having

a circumferential groove thereabout adjacent said contact sleeve end, means for securing a separate electrical conductor to each of said contact rod and said contact sleeve, an insulating jacket providing a plug handle secured about said conductor securing means, and a conductive receptacle for said plug, a conductive socket disc journaled in said receptacle having a diametrically extending socket opening therethrough to receive said plug contact sleeve therein with its end extending beyond the inner end of said socket opening, a yieldable toggle member journaled in said receptacle and secured to said disc and yieldably urging it toward each limit of its rotation, means for locking said disc against rotation in the absence of said plug and operable by said plug for releasing said disc for rotation, plug locking means secured in said receptacle in the path of rotation of said end of said plug contact sleeve to fit into said sleeve circumferential groove, a plug contact rod cooperating contact terminal insulatably supported in said receptacle in the path of said plug contact rod contact end to abut said plug contact rod contact end when said plug is locked in said socket and be yieldably urged against said contact terminal by said toggle means, said insulatably mounted contact terminal providing a positive terminal, and a negative terminal grounded to said receptacle and thus through said disc to said plug contact sleeve, whereby insertion of said plug into said disc socket opening expels said disc latch member permitting said disc and plug to rotate into plug lock cooperating position and then to contact completing position, to be held in contact completing position by said toggle means, said plug being thus locked against removal while in contact completing position, and to be rotated away from contact completing position to plug releasing position and then to disc latching position as said plug is withdrawn, and whereby a foreign object of sufficiently dissimilar shape will be non-cooperative with said locking means, and a foreign conductive object of sufficiently similar shape to expel said disc latch member and rotate said disc to contact completing position will ground the circuit through said receptacle.

2. In combination, a shock-proof locking electrical plug and receptacle comprising an axially extending contact rod, a contact sleeve insulatably supported on said contact rod having one end thereof spaced from an extending contact end of said contact rod, said contact sleeve having a circumferential groove thereabout adjacent said contact sleeve end, means for securing a separate electrical conductor to each of said contact rod and said contact sleeve, an insulating jacket providing a plug handle secured about said conductor securing means, and a conductive receptacle for said plug, a conductive socket disc journaled in said receptacle having a diametrically extending socket opening therethrough to receive said plug contact sleeve therein with its end extending beyond the inner end of said socket opening, a yieldable toggle member journaled in said receptacle and secured to said disc and yieldably urging it toward each limit of its rotation, means for locking said disc against rotation in the absence of said plug and operable by said plug for releasing said disc for rotation, said disc locking means comprising a transverse slot in said disc radially aligned with said inner end of said socket opening, a latch member, and yieldable means urging said latch member into said disc slot, said latch member having bifurcated fingers whose adjacent edges are complementary to said conical end of said contact sleeve, plug locking means secured in said receptacle in the path of rotation of said conical end of said plug contact sleeve comprising a pair of contoured prongs adjacent the disc periphery spaced apart to fit into said sleeve circumferential groove, a plug contact rod cooperating contact terminal insulatably supported in said receptacle in the path of said plug contact rod contact end to abut said plug contact rod contact end when said plug is locked in said socket and be yieldably urged against said contact terminal by said toggle

means secured in said receptacle in the path of rotation of said end of said plug contact sleeve to fit into said sleeve circumferential groove, a plug contact rod cooperating contact terminal insulatably supported in said receptacle in the path of said plug contact rod contact end to abut said plug contact rod contact end when said plug is locked in said socket and be yieldably urged against said contact terminal by said toggle means, said insulatably mounted contact terminal providing a positive terminal, and a negative terminal grounded to said receptacle and thus through said disc to said plug contact sleeve, whereby insertion of said plug into said disc socket opening expels said disc latch member permitting said disc and plug to rotate into plug lock cooperating position and then to contact completing position, to be held in contact completing position by said toggle means, said plug being thus locked against removal while in contact completing position, and to be rotated away from contact completing position to plug releasing position and then to disc latching position as said plug is withdrawn, and whereby a foreign object of sufficiently dissimilar shape will be non-cooperative with said locking means, and a foreign conductive object of sufficiently similar shape to expel said disc latch member and rotate said disc to contact completing position will ground the circuit through said receptacle.

3. In combination, a shock-proof locking electrical plug and receptacle comprising an axially extending contact rod, a contact sleeve insulatably supported on said contact rod having one end thereof spaced from an extending contact end of said contact rod, said one end of said contact sleeve being conical in shape, said contact sleeve having a circumferential groove thereabout adjacent said conical contact sleeve end, means for securing a separate electrical conductor to each of said contact rod and said contact sleeve, an insulating jacket providing a plug handle secured about said conductor securing means, and a conductive receptacle for said plug, a conductive socket disc journaled in said receptacle having a diametrically extending socket opening therethrough to receive said plug contact sleeve therein with its conical end extending beyond the inner end of said socket opening, a yieldable toggle member journaled in said receptacle and secured to said disc and yieldably urging it toward each limit of its rotation, means for locking said disc against rotation in the absence of said plug and operable by said plug for releasing said disc for rotation, said disc locking means comprising a transverse slot in said disc radially aligned with said inner end of said socket opening, a latch member, and yieldable means urging said latch member into said disc slot, said latch member being expellable by said plug, the disc slot entering portion of said latch member having bifurcated fingers whose adjacent edges are complementary to said conical end of said contact sleeve, plug locking means secured in said receptacle in the path of rotation of said conical end of said plug contact sleeve comprising a pair of contoured prongs adjacent the disc periphery spaced apart to fit into said sleeve circumferential groove, a plug contact rod cooperating contact terminal insulatably supported in said receptacle in the path of said plug contact rod contact end to abut said plug contact rod contact end when said plug is locked in said socket and be yieldably urged against said contact terminal by said toggle

means, said insulatably mounted contact terminal providing a positive terminal, and a negative terminal grounded to said receptacle and thus through said disc to said plug contact sleeve, whereby insertion of said plug into said disc socket opening expells said disc latch member permitting said disc and plug to rotate into plug lock cooperating position and then to contact completing position and then to contact completing position by said toggle means, said plug being thus locked against removal while in contact completing position, and to be rotated away from contact completing position to plug releasing position and then to disc latching position as said plug is withdrawn, and whereby a foreign object of sufficiently dissimilar shape will be non-cooperative with said locking means, and a foreign conductive object of sufficiently similar shape to expell said disc latch member and rotate said disc to contact completing position will ground the circuit through said receptacle.

4. In combination, a shock-proof locking electrical plug and receptacle comprising an axially extending contact rod, a contact sleeve insulatably supported on said contact rod having one end thereof spaced from an extending contact end of said contact rod, said contact sleeve having a circumferential groove thereabout adjacent said contact sleeve end, means for securing a separate electrical conductor to each of said contact rod and said contact sleeve, an insulating jacket providing a plug handle secured about said conductor securing means, and a receptacle for said plug comprising a pair of side frame conductive plates secured together, a conductive socket disc journaled between said plates having a diametrically extending socket opening therethrough to receive said plug contact sleeve therein with its end extending beyond the inner end of said socket opening, a yieldable toggle member journaled between said plates and secured to said disc and yieldably urging it toward each limit of its rotation, means for locking said disc against rotation in the absence of said plug and operable by said plug for releasing said disc for rotation, said disc locking means comprising a transverse slot in said disc radially aligned with said inner end of said socket opening, a latch member, and yieldable means urging said latch member into said disc slot, said latch member being expellable by said plug, plug locking means secured between said frame plates in the path of rotation of said end of said plug contact sleeve comprising a pair of contoured prongs adjacent the disc periphery spaced apart to fit into said sleeve circumferential groove, a plug contact rod cooperating contact terminal insulatably supported between said frame plates in the path of said plug contact rod to abut said plug contact rod when said plug is locked in said socket and be yieldably urged against said contact terminal by said toggle means, said insulatably mounted contact terminal providing a positive terminal, and a negative terminal grounded to said frame plates and thus through said disc to said plug contact sleeve, whereby insertion of said plug into said disc socket opening expells said disc latch member permitting said disc and plug to rotate into plug lock cooperating position and then to contact completing position, and be held in contact completing position by said toggle means, said plug being thus locked against removal while in contact completing position, and to be rotated away from contact completing position to plug releasing position and then to disc latching position as said plug is withdrawn, and whereby a foreign object of sufficiently dissimilar shape will be non-cooperative with said locking means, and a foreign conductive object of sufficiently similar shape to expell said disc latch member and ro-

position to plug releasing position and then to disc latching position as said plug is withdrawn, and whereby a foreign object of sufficiently dissimilar shape will be non-cooperative with said locking means, and a foreign conductive object of sufficiently similar shape to expell said disc latch member and rotate said disc to contact completing position will ground the circuit through said receptacle.

5. In combination, a shock-proof locking electrical plug and a receptacle comprising an axially extending contact rod, a contact sleeve insulatably supported on said contact rod having one end thereof spaced from an extending contact end of said contact rod, said one end of said contact sleeve being conical in shape, said contact sleeve having a circumferential groove thereabout adjacent said conical contact sleeve end, means for securing a separate electrical conductor to each of said contact rod and said contact sleeve, an insulating jacket providing a plug handle secured about said conductor securing means, and a receptacle for said plug comprising a pair of side frame conductive plates secured together, a conductive socket disc journaled between said plates having a diametrically extending socket opening therethrough to receive said plug contact sleeve therein with its conical end extending beyond the inner end of said socket opening, a yieldable toggle member journaled between said plates and secured to said disc and yieldably urging it toward each limit of its rotation, means for locking said disc against rotation in the absence of said plug and operable by said plug for releasing said disc for rotation, said disc locking means comprising a transverse slot in said disc radially aligned with said inner end of said socket opening, a latch member, and yieldable means urging said latch member into said disc slot, said latch member being expellable by said plug, the disc slot entering portion of said latch member having bifurcated fingers whose adjacent edges are complementary to said conical end of said contact sleeve, plug locking means secured between said frame plates in the path of rotation of said conical end of said plug contact sleeve comprising a pair of contoured prongs adjacent the disc periphery spaced apart to fit into said sleeve circumferential groove, a plug contact rod cooperating contact terminal insulatably supported between said frame plates in the path of said plug contact rod to abut said plug contact rod when said plug is locked in said socket and be yieldably urged against said contact terminal by said toggle means, said insulatably mounted contact terminal providing a positive terminal, and a negative terminal grounded to said frame plates and thus through said disc to said plug contact sleeve, whereby insertion of said plug into said disc socket opening expells said disc latch member permitting said disc and plug to rotate into plug lock cooperating position and then to contact completing position, and be held in contact completing position by said toggle means, said plug being thus locked against removal while in contact completing position, and to be rotated away from contact completing position to plug releasing position and then to disc latching position as said plug is withdrawn, and whereby a foreign object of sufficiently dissimilar shape will be non-cooperative with said locking means, and a foreign conductive object of sufficiently similar shape to expell said disc latch member and ro-

tate said disc to contact completing position will ground the circuit through said receptacle.

6. In combination, a shock-proof locking electrical plug and receptacle comprising an axially extending contact rod, a contact sleeve insulatably supported on said contact rod having one end thereof spaced from an extending contact end of said contact rod, said one end of said contact sleeve being conical in shape, said contact sleeve having a circumferential groove thereabout adjacent said conical contact sleeve end, means for securing a separate electrical conductor to each of said contact rod and said contact sleeve, an insulating jacket providing a plug handle secured about said conductor securing means, and a receptacle for said plug comprising a pair of side frame conductive plates secured together in spaced parallel relation, outward flanges on said plates providing receptacle mounting means, a conductive socket disc journaled between said plates having a diametrically extending socket opening therethrough to receive said plug contact sleeve therein with its conical end extending beyond the inner end of said socket opening, a yieldable toggle member journaled between said plates and secured to said disc and yieldably urging it toward limit of its rotation, means for locking said disc against rotation in the absence of said plug and operable by said plug for releasing said disc for rotation, said disc locking means comprising a transverse slot in said disc radially aligned with said inner slot in said disc, a latch member, and yieldable means urging said latch member into said disc slot, said latch member being expellable by the plug, the disc slot entering portion of said latch member having bifurcated fingers, plug locking means secured between said frame plates in the path of rotation of said end of said plug contact sleeve, a plug contact cooperating contact terminal insulatably supported between said frame plates in the path of the plug contact end to abut said plug contact end when the plug is locked in said socket and be yieldably urged against said contact terminal by said toggle means, said insulatably mounted contact terminal providing a positive terminal, and a negative terminal grounded to said frame plates and thus through said disc to said plug contact sleeve.

7. For use with a one prong electrical plug, a shockproof receptacle for the plug comprising a pair of side frame conductive plates secured together, a conductive socket disc journaled between said plates having a diametrically extending socket opening therethrough to receive a plug therein with its end extending beyond the inner end of the socket opening, a yieldable toggle member journaled between said plates and secured to said disc and yieldably urging it toward each limit of its rotation, means for locking said disc against rotation in the absence of the plug and operable by the plug for releasing said disc for rotation, said disc locking means comprising a transverse slot in said disc radially aligned with said inner end of said socket opening, a latch member, and yieldable means urging said latch member into said disc slot, said latch member being expellable by the plug, the disc slot entering portion of said latch member having bifurcated fingers, plug locking means secured between said frame plates in the path of rotation of said end of said plug contact sleeve, a plug contact cooperating contact terminal insulatably supported between said frame plates in the path of the plug contact end to abut said plug contact end when the plug is locked in said socket and be yieldably urged against said contact terminal by said toggle means, said insulatably mounted contact terminal providing a positive terminal, and a negative terminal grounded to said frame plates and thus through said disc to said plug contact sleeve.

8. For use with a one prong electrical plug, a shockproof receptacle for the plug comprising a pair of side frame conductive plates secured together, a conductive socket disc journaled between said plates having a diametrically extending socket opening therethrough to receive a plug therein with its end extending therebeyond the inner end of the socket opening, a yieldable toggle member journaled between said plates and secured to said disc and yieldably urging it toward each limit of its rotation, means for locking said disc against rotation in the absence of the plug and operable by the plug for releasing said disc for rotation, said disc locking means comprising a transverse slot in said disc radially aligned with said inner end of said socket opening, a latch member, and yieldable means urging said latch member into said disc slot, said latch member being expellable by the plug, the disc slot entering portion of said latch member having bifurcated fingers, plug locking means secured between said frame plates in the path of rotation of said end of said plug contact sleeve comprising a pair of contoured prongs adjacent the disc periphery spaced apart to fit into a plug circumferential groove, a plug contact rod cooperating contact terminal insulatably supported between said frame plates in the path of said plug contact rod contact end to abut said plug contact rod contact end when said plug is locked in said socket and be yieldably urged against said contact terminal by said toggle means, said insulatably mounted contact terminal providing a positive terminal, and a negative terminal grounded to said frame plates and thus through said disc to said plug contact sleeve, whereby insertion of said plug into said disc socket opening expells said disc latch member permitting said disc and plug to rotate into plug lock cooperating position and then to contact completing position, and be held in contact completing position by said toggle means, said plug being thus locked against removal while in contact completing position, and to be rotated away from contact completing position to plug releasing position and then to disc latching position as said plug is withdrawn, and whereby a foreign object of sufficiently dissimilar shape will be non-cooperative with said locking means latch member fingers and will be deflected from said latch member by said deflector plates, and a foreign conductive object of sufficiently similar shape to expell said disc latch member and rotate said disc to contact completing position will ground the circuit through said receptacle.
